UNITED STATES PATENT OFFICE.

LINTON GREGORY STABLES, OF LOS ANGELES, CALIFORNIA.

AUTOMATIC SAFETY-GUARD.

1,400,835.

Specification of Letters Patent. Patented Dec. 20, 1921.

Application filed July 26, 1920. Serial No. 398,870.

To all whom it may concern:

Be it known that I, LINTON GREGORY STABLES, a citizen of the United States, residing at Los Angeles, in the county of Los Angeles and State of California, have invented new and useful Improvements in Automatic Safety-Guards, described and claimed in the annexed specification.

My invention relates to improvements in automatic safety guards designed to be attached to machine tools, more particularly to those tools which have a manually operated period or cycle of operation such as punch presses and the like; the objects being 10 to provide a safety guard which will operate automatically before the machine operates and one in which the guard must travel fully into its operative position as such before the machine upon which it is installed can be 15 thrown into operation; the device consisting of the novel features herein shown, described and claimed.

With reference to the drawings:

Figure 1 is a side elevation of a punch 25 press showing the invention in a raised position and out of action.

Fig. 2 is a side elevation of a punch press showing the invention held from being thrown into operation by a hand of an operator.

Fig. 3 is a side elevation of a punch press with the invention in operative position as a guard.

Fig. 4 is a front elevation of a punch press 35 showing a front view of the invention in a position as shown in Fig. 1.

Fig. 5 is a side elevation of a punch press showing the invention operated by a hand lever and with a guard member and a treadle 40 removed.

The invention is herein shown attached to a punch press 1 comprising a frame carrying legs 2, 2, a table 3 and an upwardly extending standard 4.

At the top of the standard is mounted the 45 punch press mechanism consisting of a fly wheel 5, a shaft 6, and a punch element 7, the press being operated in the conventional manner.

The press has a releasing mechanism comprising a treadle 8, pivoted to one of the legs 2, to which is pivotally attached a link 28 the upper end of the link being pivoted to a rock arm 10 and from the rock arm 10 a 55 second link 11 extends upwardly connecting with any of the conventional means by which

such devices are released. On the table 3 is placed a die 12.

More specifically the present invention comprises a shell 13 positively mounted to 60 the side of the frame 2.

Rotatably mounted within the shell is a block 14 having a deep notch 15. Disposed at the top of the shell 13 is a guide 16 slidably carrying a pin 17, the pin being pivotally connected to the rock arm 10 by a link 18.

An arm 19 is fixed across the face of the block 14 which extends along the side of the press toward the front.

An open frame 20, of screen or bars, is mounted upon the outer end of the arm 19, which is adapted to partly surround the die 12 and lay closely above the table 3. The frame or guard 20 extends across the front 75 of the die and the side opposite that which is carried by the arm 19 is carried by a second arm 21 which extends backwardly and is pivotally connected to the standard 4 opposite the block 14.

The pins 19^a and 19^b extending from the side of the standard 4 form stops above and below the arm 19.

An operating treadle 22 is pivoted to a leg 2 and is disposed above the treadle 8, it 85 being connected to the arm 19 by a link 9. Where the link 9 is connected with the treadle 22 it passes slidably through a block 24 which is fixed to the treadle and extends therebelow carrying a spring 25 positioned 90 between the block and nuts 26 which are screw seated upon the end of the link.

In the operation of the device, the press and safety guard being in a position as shown in Fig. 1, the treadle 22 is pressed down by the foot of the operator thereby moving downwardly the guard 20 and rotating the block 14. The device is so adjusted that when the guard 20 is down upon the step 19^b the notch 15 is exactly under the 100 pin 17 and the treadle 22 has been pressed down upon the treadle 8. With a further pressure of the operator upon the treadle 22 the treadle 8 is pressed down thus rocking the arm 10 through the link 9 and the pin 105 17 is thereby entered into the notch 15 thus allowing the arm 10 to move far enough to trip the press by means of the link 11.

Should the operator's hand, as shown in Fig. 2, or other object be caught under the 110 descending guard 20 and possibly upon the die the downward movement of the treadle

22 would compress the spring 25 as it could not carry the guard down upon the stop and therefore the notch 15 would not be rotated far enough for the pin 17 to enter the notch 5 15 and though the operator might bear his weight upon the treadles 8 and 22 the pin 17 would simply rest upon the periphery of the block 14 and the press could not be tripped.

The same result would be had should the 10 operator unintentionally put his foot directly upon the treadle 8.

On some devices such as paper cutting machines and the like, where the guard 20 could not be used to advantage, the remainder of 15 the device may be operated as a safety appliance in which case the block 14 could be rotated as shown in Figs. 1, 2, 3 and 4 or by hand as shown in Fig. 5.

In Fig. 5 it will be noted the lever 22 20 link 23 and guard 20 are not shown and the arm 19 is formed into a handle, it being the intention that when the device is installed upon such machines as paper cutters and the like which are tripped by hand the operator would use one hand to throw the 25 block 14 into position and the other hand then to trip the machine, thereby eliminating the necessity of the guard 20.

It is obvious that the form of the block 30 14 and its mounting 13 might be changed and the connecting and operating mechanism of the invention altered in many ways to meet the especial requirements of the various machine tools upon which it might 35 be installed and that other changes might be made in the structural detail of the invention as shown without departing from the spirit and intent thereof as claimed.

Claims:

40 1. In an automatic safety guard in combination, a machine tool having a releasing mechanism and adapted to be released to travel through a certain cycle of operation, a guard element pivotally mounted upon the 45 tool and adapted to swing into and out of operative position with each cycle of the tool, a locking means mounted upon the pivotal mounting of said guard, means mounted upon the releasing mechanism of said tool 50 adapted to engage the locking means whereby the tool releasing mechanism can be operated only when the guard element is fully in operative position.

2. In combination in an automatic safety 55 guard, a machine tool having a releasing mechanism and adapted to operate intermittently, a guard element pivotally mounted upon the tool and adapted to swing into and out of operative position with each cycle of 60 operation thereof, a grooved block fixed to the pivotal mounting of the guard element

and adapted to move therewith, means mounted upon the tool releasing mechanism and adapted to engage the groove of the block when the guard element is in operative position whereby the tool releasing mechanism may be operated. 65

3. In an automatic safety guard in combination, a machine tool having a releasing mechanism and adapted to operate intermittently, a guard element pivotally mounted upon the tool and adapted to swing into and out of operative position, a casing fixed to the frame of the tool and surrounding the pivotal mounting of the guard element, a 75 notched block mounted within the casing and adapted to rotate with the swinging of the guard element, a guide positioned adjacent the casing, a pin slidably mounted in the guide and adapted to slide into the notch 80 of the block, when the guard element is in operative position, a link connecting the pin with the tool releasing mechanism and means for swinging the guard element into and out of operative position. 85

4. An automatic safety guard comprising a guard element, having a pivotal bearing, a casing adapted to surround the bearing and having a pin guide in its wall, a notched block fixed to the guard bearing and adapted 90 to rotate therewith within the casing, a pin slidably mounted in the pin guide and adapted to slide freely into the notch of the block and to be connected at its outer end with a machine tool releasing mechanism, a 95 treadle, a link connecting flexibly the treadle with the guard element.

5. In an automatic safety guard in combination, a machine tool having a releasing mechanism and adapted to be released to travel through a certain cycle of operation, a guard element pivotally mounted upon the tool and adapted to swing into and out of operative position with each cycle of the tool, a locking means fixed to the pivotal mounting 100 of the guard element, means mounted upon the releasing mechanism of the tool adapted to engage the locking means of the guard element to allow an operation of the tool only when the guard element is fully in 105 operative position, a treadle, a link connecting with the guard element and having its lower end passing slidably through the treadle and a retractile spring positioned to bear against the treadle and against the 110 lower end of the link whereby the treadle may be moved farther than the necessary distance to move the guard element into operative position. 115

In testimony whereof I have signed my 120 name to this specification.

L. GREGORY STABLES.
